POWDER BOX

Walter Zipper, Vienna, Austria

Application December 13, 1933, Serial No. 702,249
In Austria August 21, 1933

6 Claims. (Cl. 132—83)

This invention relates to a powder box which, while being of pleasing shape and of comparatively light weight, and convenient in use, permits of the mounting of as large a mirror as is possible on the inner side of the lid, and of the complete utilization of the supply of powder carried by means of the powder puff or pad, and which enables stick-shaped toilet requisites, for example a lip stick and a rouge stick, to be stowed in a compartment separated from the powder storage space in a simple manner which does not appreciably diminish the storage capacity of the box. These advantages are obtained in accordance with the invention by virtue of the arrangement that the lower or base portion occupied by the powder-puff or pad and powder is in the shape of a wedge tapered down towards the hinge end of the box, and is closed over by a flat lid provided on the inner side with a mirror, in a manner known per se. The wedge-shaped base portion is preferably of rectangular or approximately rectangular shape, in plan, and is provided, at the extreme end furthest removed from the hinge, with a cylindrical chamber for the reception of stick-shaped toilet requisites.

In the accompanying drawings Fig. 1 is a side elevation of a powder box made in accordance with the invention. Fig. 2 is a top plan view of the box closed. Fig. 3 is a top plan view of the box open. Fig. 4 is a transverse vertical section through the box in the position indicated in Fig. 3. Fig. 5 is a plan view of a tubular casing which holds the stick-shaped toilet requisites within the box. Fig. 6 is a fragmentary transverse section on a slightly enlarged scale on the line B—B of Fig. 2. Fig. 7 is a side elevation of a box illustrating another form the invention may take, and Figs. 8, 9, and 10 are top plan views of optional forms of powder boxes embodying the invention.

In the constructional example shown in Figs. 1 to 4 the base portion *a* of the powder box is of rectangular or approximately rectangular outline, and is closed over by a suitably shaped flat lid *b* which is provided on its inner side with a mirror *c*. The base portion *a* is in the shape of a wedge (Figs. 1 and 4) tapered down towards the hinge end of the box, and the depth of the storage space *f* for the powder is correspondingly reduced towards the hinge *d* (Fig. 4). The base portion *a* and the lid *b* consists of sheet metal, but these parts, and more particularly the base portion *a*, can also be manufactured of light metal or of any one of the known suitable artificial compositions, for example by pressing or die

casting. The storage space *f* is covered over by a sieve *g* (Fig. 4) consisting of thin, wide-mesh fabric or the like, through which the powder passes and can be taken up by means of the puff or pad *h*.

The shaping of the base portion *a* in the form of a wedge provides a number of advantages over the known powder boxes in which the base portion constitutes a tray which becomes gradually shallower towards the outer edge. In consequence of this wedge shape of the powder box according to the present invention, the center of gravity of the base portion *a* is shifted from the middle towards the forward end, so that a lighter weight of the base portion *a* is sufficient; in this manner the box, when placed in the open condition (Fig. 4) upon a supporting surface, is prevented from tilting over by the lid *b* carrying the relatively heavy mirror *c*, so that not only is a spilling of powder effectually avoided, but the mirror *c* is conveniently retained in the inclined position required for use (Fig. 4). The mirror *c* can thus be made larger, other conditions being equal, than would otherwise be practically possible, and can be allowed to extend close up to the edge of the lid. A further advantage consists in the fact that the supply of powder can be conveniently used up to the very last, whereas with the above-mentioned known types of powder-boxes a portion of the powder clogs at the outer edge of the storage furrow or tray, which becomes constantly shallower towards the outer edge, between the bottom of the latter and the covering sieve *g*, and cannot be extracted for use. In the case of a powder-box constructed in accordance with the present invention, on the other hand, this clogging of the powder can only take place at a small portion of the circumference, while at the same time the total storage space is larger than in the case of the known powder-boxes, under otherwise similar conditions. In the deepest part of the storage space *f*, and separated therefrom by a partition, there can be inserted a stick-shaped toilet requisite, for example a lip stick or a rouge stick.

The lid of the powder-box, and if desired the base portion *a* can also be very slightly curved (Fig. 7), the wedge shape being, however, substantially retained.

The wedge-shaped cross-section or outline of the base portion *a* can clearly also be retained in connection with a plan or outline shape which is other than rectangular, for example trapezoid-shaped (Fig. 8), polygonal (Fig. 9), or curved (Fig. 10), or even circular or elliptical; only in the

latter case the housing of the stick-shaped toilet requisites is not possible in so simple a manner as with the other shapes.

The stick-shaped toilet requisites are preferably housed in a chamber completely separated from the storage space *f*. For this purpose there is provided at the end of the base portion *a* remotest from the hinge *d* a compartment *i* extending transversely of the box, this compartment being open to both sides, and serving for the reception of one or two stick-shaped toilet requisites, of a lip-stick and a rouge-stick, or, if desired, of a powder-stick. These latter do not normally project from the base portion *a*, and are adapted to become thrust out slightly (see Fig. 3) on the opening of the box. This purpose is served by the following arrangement.

In the constructional example shown (Figs. 1-6) there is arranged in the compartment *i* a cylindrical tubular casing *j* of thin sheet metal, which is locked against rotation, and in which there are slidably fitted the two likewise tubular holders *k* for a lip-stick *m* and a rouge-stick *n*, which are indicated in broken lines in Fig. 5. The stick holders *k* are provided with small guide pins *p* which project outwards through two oppositely inclined oblique slots *q* in the tubular casing *j* (Figs. 5 and 6). On the tubular casing *j* there is rotatably mounted a wide sheet metal ring *r* which is disposed in a recess *s* (Figs. 2 and 3) in the base portion *a*, and which carries a projection *t* which serves as an operating knob or button and as a movement-limiting stop, and which in the position of closure (Fig. 2) clasps the edge of the lid *b* and locks or holds it closed. Further, the ring *r* is provided on the inside with a longitudinal groove *u* (Fig. 6) into which the above-mentioned guide pins *p* on the stick holders *k* are arranged to project. If the closing ring *r* be turned for opening (arrow I, Fig. 6), its longitudinal groove *u* moves the pins *p*, and therefore also the stick holders *k*, in an axial sense (double arrow II, Fig. 3), so that the ends of the two stick-shaped toilet requisites *m*, *n*, or their caps, are caused to emerge (Fig. 3). The lip-stick can then be completely withdrawn for use, while from the projecting end of the rouge-stick *n*, after the removal of its cap, the required quantities can be taken with the aid of a puff or pad. On the closing of the powder-box, the stick-shaped toilet requisites *m*, *n* are retracted by the turning back of the ring *r*, so that they come into position once more entirely within the cylindrical tubular casing *j* (Fig. 2).

In the same manner as a lip- and rouge-stick, a stick-shaped powder-dispenser of a known type can be arranged in the compartment *i*.

By virtue of the described manner of housing the stick-shaped toilet requisites, these latter are prevented from coming in contact with the powder, and are so retained in position that they do not shake about in the box.

What I claim is:

1. A receptacle having an opening, two members for closing the opening, a tube on one mem-

ber for holding an article, means on the member carrying the tube for engaging or releasing the other member, and means controlled by the first named means for causing the article to move in the tube.

2. In a receptacle comprising a frame of two members hinged together, a tube on one member, a catch on the tube for engaging or releasing the other member, a receptacle in the tube, and means controlled by the catch for causing the receptacle to move into the tube when the catch engages the other member and to move out of the tube when the catch releases the other member.

3. In a receptacle comprising a frame of two members, a tube on one member arranged longitudinally of the receptacle for holding one or more articles, a ring surrounding the tube at about its center and movable circumferentially thereabout, a catch on the ring for engaging the other member, when the ring is in one position, and means engaged by the ring as it moves to engage the other member to cause the articles to recede into the tube and to cause the articles to project from the ends of the tube when the ring is moved to remove the catch from the other member.

4. In a receptacle comprising a frame of two members, a tube on one member arranged longitudinally of the receptacle for holding one or more articles, a ring surrounding the tube at about its center and movable circumferentially thereabout, a catch on the ring for engaging the other member, when the ring is in one position, means engaged by the ring as it moves to engage the other member to cause the articles to recede into the tube and to cause the articles to project from the ends of the tube when the ring is moved to remove the catch from the other member and movable covers for the articles engaging the tube.

5. In a receptacle comprising a frame of two members, a tube on one member arranged longitudinally of the receptacle, a ring surrounding the tube at about its center and movable circumferentially thereabout, a catch on the ring for engaging the other member when the ring is in one position, receptacles in the tube, and means engaged by the ring as it moves to engage the other member to cause the receptacles to recede into the tube and to cause the receptacles to move toward the ends of the tube when the ring is moved to remove the catch from the other member.

6. In a receptacle comprising a frame of two members, a tube on one member arranged longitudinally of the receptacle, a ring surrounding the tube at about its center and movable circumferentially thereabout, a catch on the ring for engaging the other member when the ring is in one position, receptacles in the tube, means engaged by the ring as it moves to engage the other member to cause the receptacles to recede into the tube and to cause the receptacles to move toward the ends of the tube when the ring is moved to remove the catch from the other member and removable covers for the receptacles.
